MODULATION

Jarrett Lewis Hathaway, Manhasset, N. Y., assignor to Radio Corporation of America, a corporation of Delaware

Application October 17, 1942, Serial No. 462,361

13 Claims. (Cl. 250—6)

This application discloses a new and improved modulation method and means for signalling by timing modulated waves referred to herein as wave length modulated waves.

My improvement involves the use of combined wave length and amplitude modulation in a system used for transmitting wave length modulating signals, and has as an object the reduction of the noise level in a wave length modulation system. Considered from a different viewpoint, my method and means are for the purpose of improving in a wave length modulation system the signal to noise ratio.

In describing my invention in detail reference will be made to the attached drawings wherein

Figures 1 and 2 are curves used in describing one source of noise or distortion in a wave length modulation system and the manner in which the same is caused.

Figure 3 illustrates a modulation system arranged in accordance with my invention wherein in timing modulation is accomplished and wherein in amplitude modulation is simultaneously provided to decrease the noise level in the system thereby improving the signal to noise ratio; Figure 4 illustrates a receiver arranged for the reception of wave energy modulated in accordance with my invention; while Figure 3a illustrates a modification of the arrangement of Figure 3.

During tests on the comparison of the amplitude modulation with wide and narrow band systems of frequency modulation, it has been observed that with no modulation, noise levels are very low on both of the frequency modulation systems compared with the amplitude modulation system. However, it was also noted that noise arose with modulation on the frequency modulation systems, whereas it stayed essentially constant on the amplitude modulation system. The result, as measured by a distortion meter, is that for full level modulation, less noise is present on the amplitude modulation system than on either the wide band or narrow band frequency modulation systems.

The noise level increase with deviation in timing modulation systems is, it is believed, due in part at least to the fact that in passing a wave length modulated wave through selective circuits, the noise to signal ratio is increased when the wave is swung off carrier because of the rounding off of the characteristics of the circuits wherein the selectivity of the system resides. This can be seen by inspection of Figure 1, wherein curve A designates roughly the characteristic of the se-

lectivity system used in a wave length modulated transmitter and in particular of such selective circuits used in the receiver of a wave length modulation system. The selectivity characteristic at A results in an increase in the noise to signal ratio N/S as the carrier f_c deviates from zero modulation in either direction, as shown by the curve B in Figure 2.

The noise rise observed in reception is also due in part to the improper cancellation of noise when the incoming wave is shifted in frequency from its mean frequency. That is, the discriminator is normally tuned to the carrier frequency where noise on each side cancels out, but when modulation occurs the noise is no longer cancelled.

The increase in noise level or decrease in signal to noise ratio puts an added burden on any limiter used in the system at the transmitter or receiver. At the receiver the burden on the limiter is increased considerably because the signal has fallen off in strength and the limiter must be designed to operate on less signal and, as a consequence, the limiter at the receiver must be of better design and regulation or the gain of the receiver must be appreciably higher.

To cure this defect, I propose to modulate the amplitude of the wave length modulator output in accordance with the modulation potential so that the output is increased in amplitude substantially proportionally with the frequency deviation in either direction from zero modulation or carrier frequency. That is, in the presence of no modulation or carrier frequency the output will be of a given nominal value. As the modulation is applied, the output amplitude will be increased substantially proportionally as the frequency is shifted in either direction from the carrier frequency.

In my system no special or exact relation between the amount of amplitude modulation and the wave deviation in accordance with the modulation is required. It is essential however that the amplitude increase with deviation and this increase is substantially proportional to the frequency shift. In a sense then, the amplitude modulation applied to the wave length modulator in my system may be also represented by the curve B, Figure 2. Thus I obtain the desired improvement of the signal to noise ratio and the reduction of noise during modulation and especially during high level modulation. In my system the output at the carrier frequency or zero modulation may be of the desired nominal value.

As stated above, my system for reducing noise on frequency modulation reception during modu-

lation involves a combination of wave length and amplitude modulation. In Figure 3 I have shown an embodiment of my system comprising a wave length modulator at 10 including a source of oscillations and a means connected with said source of oscillations and with a source of modulating potentials 12 to accomplish in 10 wave length modulation of the carrier. For example, I may use in 10 a timing modulated transmitter of the Crosby type, such as, for example, illustrated in Crosby U. S. Patent No. 2,279,659, dated April 14, 1942. The transmitter may include frequency multipliers and amplifiers and has an output stage comprising tubes 16 and 18. The input electrodes of the tubes 16 and 18 are supplied with wave length modulated wave energy and the output electrodes thereof are coupled by tuned circuit 20 to a utilization means, such as, an antenna or to lines connected with a utilization means directly or by way of additional amplifiers and frequency multipliers.

The output electrodes of tubes 16 and 18 are supplied direct current by a line 24 connected to the cathodes 27 and 29 of a pair of rectifiers 26 and 28, the anodes of which are tied together and connected to a source of direct current not shown having a negative terminal connected to the cathodes of tubes 16 and 18. The direct current potential circuit for tubes 16 and 18 is from the positive terminal of the source to the anodes of tubes 26 and 28 through the tubes to the cathodes 27 and 29, thence by line 24 to the anodes of tubes 16 and 18, to the cathodes of tubes 16 and 18 and thence to the negative terminal of the direct current source. The resistance 48 is placed in parallel with the internal impedances of tubes 26 and 28 and acts as an additional path for the direct current to reach the anodes of tubes 16 and 18.

The control grids of tubes 26 and 28 are coupled by transformer 30, or any other suitable phase inversion system known to the art, to the source of modulating potentials 12. Bias for these tubes is supplied by way of resistor 34 from any source, such as, for example, source 36. The tubes 26 and 28 are biased nearly to cut off by way of resistors 34, and the source 36 may be bypassed for potentials of the order of modulating frequency by condenser 40.

In my system, as stated above, modulation is applied to the wave length modulator 10 in source 12 and the carrier therein is modulated in wave length in a conventional manner. Simultaneously, amplitude modulation is supplied to the transformer 30 and the bias of the tubes 26 and 28 is adjusted so that on peaks, either positive or negative, the carrier is increased. The transmitted wave is picked up by a receiver such as shown in Figure 4. This amplitude modulation is then smoothed in the receiver by fast action automatic gain or volume control or by conventional limiters. Thus, the signal on peak modulation is stronger relative to the interfering noise than it would be with conventional frequency modulation only.

In the modification of Figure 3, the carrier may be normally adjusted to be low in amplitude. The bias on the grids of tubes 26 and 28 is adjusted to approximately cut off. The bias may be above or below cut off. When the bias is greater than cut off the entire anode supply current to tubes 16 and 18 is passed thru resistor 48 in the absence of modulation since the impedances of tubes 26 and 28 are infinite. As modulation is applied the wave length of the car-

rier in 10 is deviated in accordance with the modulating potentials. At the same time the modulation is applied by transformer 30 to the grids of 26 and 28, the combined impedance thereof, which shunts resistance 48, is lowered and the direct current potential applied to the anodes of tubes 16 and 18 increases to thereby increase the intensity of the output as the carrier deviates in either direction from zero modulation. The tubes 26 and 28 may be biased close to, or even at, or beyond cut off. Since the tubes 26 and 28 are differentially excited by the modulating potentials, the grid of one tube or the other swings positive on both the positive and negative cycles of the modulating potentials.

In a modification shown in Figure 3a, the transformer 30 supplies its output to a tube 51 of the duo-diode-triode type. The modulation potentials are rectified in the diode section and appear across resistor 50 to be impressed on the control grid 52 so that both halves of the modulation cycle are amplified and appear in the transformer 54, the secondary winding of which is in the direct-current-supply circuit for tubes 16 and 18 at points marked Y. The transformer 30 of Figure 3a has its primary connected to the modulation potential source at points marked X to thereby replace the amplitude modulator of Figure 3. This system, as in Figure 3, increases the carrier amplitude on both + and - peaks of modulation as the carrier is deviated from zero modulation. The secondary terminals marked Y are connected in the high voltage supply line to tubes 16 and 18 with such polarity that this high voltage is increased during both the positive and the negative excursions of modulation, which implies a reduction of high voltage at times when the modulating voltage crosses the zero axis. The action here, which is an increase of the potential in the anodes of tubes 16 and 18 as the carrier is swung from no modulation position in either direction, is apparent from the preceding description, it is believed.

The amplitude modulation may be applied in the transmitter at any suitable point, whether in the output stage or one of the earlier stages. It may be applied in the anode supply as shown or in the screen grid circuits or in the grid circuits if desired.

What I claim is:

1. In a system wherein the instantaneous frequency of wave energy is swung in proportion to the intensity of signaling current, the method of increasing the signal to noise ratio which includes the following steps, increasing the amplitude of the wave energy as the frequency thereof deviates from carrier frequency in one direction, increasing the amplitude of the wave energy as the frequency thereof deviates from carrier frequency in the other direction and maintaining the signalling channel width substantially constant during said operation.
2. In a system wherein the instantaneous frequency of wave energy is deviated through a range considerably greater than 90° in accordance with signals, the method of operation which includes the following steps, increasing the amplitude of the deviated carrier as the same deviates from carrier condition in one direction an amount which grows as the deviation from the carrier condition increases, increasing the amplitude of the deviated carrier as the same deviates from the carrier condition in the other direction an amount which grows as the deviation from the

carrier condition increases and maintaining the signalling channel width substantially constant during said process.

3. The method of demodulating a wave of the nature recited in claim 1 which comprises, limiting off said amplitude changes and demodulating the instantaneous frequency changes.

4. The method of demodulating wave energy of the nature recited in claim 2 which comprises, limiting off said amplitude changes and demodulating the instantaneous frequency changes.

5. The method of compensating noise and distortion in a wave length modulation system wherein the carrier is deviated about a mean value in accordance with modulating potentials and wherein selectivity of the circuits and discriminator circuit characteristics introduce noise and distortion which increases with deviation of the carrier from the no modulation position which includes the following steps in the transmitter rectifying the modulation potentials and increasing the amplitude of the wave length modulated wave in accordance with the rectified potentials in both the positive and negative polarities thereof.

6. The method of signalling which includes the following steps, generating carrier wave energy the frequency of which is modulated in accordance with signals and increasing the amplitude of said frequency modulated wave substantially in proportion to changes of the amplitude of the signals in both directions from a base value to increase the signal to noise ratio during transmission.

7. A signaling method including with the steps recited in claim 1 the following steps, transmitting said amplitude varied instantaneous frequency modulated wave, receiving the transmitted wave, limiting the amplitude of the received wave to remove said amplitude variations and demodulating the limited wave.

8. In a system wherein the instantaneous frequency of wave energy is swung through more than 90° in proportion to the intensity of signalling current, a modulator for increasing the amplitude of the wave energy in both directions of swing to reduce losses due to circuit selectivity in the transmitter or receiver.

9. In a signalling system, a wave length modulated wave generator and transmitter, a wave length modulated wave receiver including a pick-up element and a demodulator, band pass circuits in said system for selecting the generated wave energy and passing the same along, and means for compensating for distortion introduced in said wave energy by said band pass circuits comprising a modulator for increasing the amplification of the wave length modulated wave energy

when deviations thereof approach the limits of said band pass circuits.

10. A method as recited in claim 6 including these additional steps, picking up said wave energy, limiting off said amplitude variations and demodulating the limited wave energy.

11. In a signalling system wherein wave energy of carrier wave frequency has its instantaneous phase shifted in accordance with signals through

10 a range considerably greater than 90°, transmitting means associated with said generator and signal receiving and amplifying means, a selective circuit in at least one of said means, said selective circuit being arranged to pass therein 15 the shifted wave energy and means for reducing the effects of the characteristics of said selective circuit on said shifted wave energy comprising an amplitude modulator through which said wave energy is passed, and connections in said amplitude modulator for increasing the amplitude of the shifted wave energy substantially in proportion to its instantaneous phase excursions above or below carrier frequency while maintaining the signal channel width substantially constant.

25 12. In a wave length modulation system, a wave length modulated transmitter including a source of modulating potentials and carrier wave length modulating means coupled thereto with an output stage therefor comprising an electron discharge amplified tube having output electrodes coupled in an output circuit and connected with a source of direct current, and means for improving the signal to noise ratio of the radiated energy 30 including a full wave rectifier having input electrodes coupled to said source of modulating potentials and having output electrodes, and connections including the impedance between the output electrodes of said rectifiers in the connections between the output electrodes of said amplifier tube and said source of direct current.

35 13. In a wave length modulation system, a wave length modulated transmitter including a source of modulating potentials and carrier wave length modulating means coupled thereto with an 40 output stage therefor comprising an electron discharge amplifier tube having output electrodes coupled in an output circuit, a source of direct current, a full wave rectifier having input electrodes coupled to said source of modulating potentials and having output electrodes, an amplifier coupled to said last named output electrodes, a transformer having a primary winding coupled to said amplifier said transformer having 45 a secondary winding and connections connecting said source of potential and said secondary winding in series with the output electrodes of said amplifier tubes.

JARRETT LEWIS HATHAWAY.
